UNITED STATES PATENT OFFICE.

ELLON S. HILL, OF BOSTON, MASSACHUSETTS.

BOX AND BLANK THEREFOR.

1,174,417.

Specification of Letters Patent. Patented Mar. 7, 1916.

Application filed March 18, 1915. Serial No. 15,163.

To all whom it may concern:

Be it known that I, ELLON S. HILL, a citizen of the United States, and resident of Boston, in the county of Suffolk and State 5 of Massachusetts, have invented certain new and useful Improvements in Boxes and Blanks Therefor, of which the following is a specification.

This invention relates to boxes made from 10 paper board or so-called "box-board," and the object of the invention is to produce cheap and strong box members or blanks with reinforcing material, wherever strengthening or reinforcing is required.

15 To this end the invention consists in the improvements in a box member and a blank therefor substantially as hereinafter described and claimed.

In the process of making or setting up of 20 boxes it has been usual and necessary, because of the weakness of the box-board, to reinforce some or all of the corners or angles of the boxes. After the setting up and reinforcing has been completed the box and lid 25 are usually covered on the outside with a thin, surfaced or highly finished paper, to give them a better appearance.

While the box or receiving member does 30 not so frequently require this strengthening as the cover or lid therefor, I do not limit my invention to either member of the box, or to the blank used either for the receptacle member or the blank used for the cover or lid member.

35 It is customary in order to strengthen a box member, made from box-board, to employ stays in the form of adhesive paper or cloth strips and occasionally string or cord, such strengthening strips being placed along 40 or around the corners or angles of the box after it has been formed or shaped, or during the process of forming or setting up. The placing of these stays on the box members involves considerable expense and diffi- 45 culty whether done by hand or machinery, due to the necessity of making the stays positively adhere and also at the same time exactly locating them at the place of greatest strain or pressure.

50 In carrying out my invention I provide a flat blank having longitudinal creases near two opposite edges defining the bases of two longitudinal flanges and slots at the opposite ends of said creases defining the inner 55 edges of reinforcing tongues and the ends of two lateral flanges, the blank being also

creased to define the bases of said lateral flanges, the longitudinal flanges and tongues being provided with reinforcing strips connecting said flanges with the tongues. In forming a box from said blank the flanges are bent inwardly from the bottom portion of the blank and the tongues are bent to lie against the inner sides of the lateral flanges. Preferably each flange is of greater width 65 than the said tongues, and is creased longitudinally to define the bases of flaps which are bent inwardly to cover said tongues and reinforcing strips, the said flanges and strips forming in the completed box a laminated 70 wall.

Of the accompanying drawings forming a part of this specification: Figure 1 represents a plan view of a blank embodying my invention; Figs. 2, 3 and 4 represent fragmentary perspective views illustrating successive steps in the operation of forming the box; Fig. 5 represents a section on line 5—5 of Fig. 4; Fig. 6 represents a section on line 6—6 of Fig. 4.

The same reference characters indicate the same or similar parts in all the views.

The blank represented by Fig. 1 comprises a body portion 12, two longitudinal flanges 13, and two lateral flanges 14, said blank and flanges being integral and made from box-board or other suitable material. The blank is provided with longitudinal creases 15 defining the bases of the flanges 13 and with lateral creases 16 defining the bases of the flanges 14. The blank is provided at opposite ends with slots 17 defining the ends of the lateral flanges 14 and the inner edges of reinforced tongues 18 which constitute extensions of the longitudinal flanges 13. To 95 the flanges 13 and tongues 18 are cemented reinforcing strips 19, preferably of a relatively thin paper of superior textile strength, such as the so-called Kraft paper, or of cloth, said strips extending across the lines on which the tongues 18 are bent, as hereinafter described, said lines being continuations of the creases 16. The flanges are widened and are longitudinally creased at 20 to define the bases of flaps 13^a on the flanges 13, and flaps 14^a on the flanges 14.

In forming a box member from the described blank the longitudinal flanges 13 are bent from the body portion 12, and the tongues 18 are bent inwardly, as indicated 110 by Fig. 2. The lateral flanges 14 are then bent against the tongues 18, as indicated by

Fig. 3, the flanges 14 being preferably cemented to the tongues. The flaps 13^a and 14^a are then bent, as indicated by Fig. 4, and cemented respectively to the flanges 13 and 14, the flaps 14^a being also cemented to the tongues 18.

The last described operation completes the box member, which is composed of a body portion and a rectangular laminated wall, as clearly shown by Figs. 4, 5 and 6, the corner portions of said wall having a greater number of layers than the intermediate portions. It will be seen that the corners of the box member wall are reinforced by the reinforcing strips 19, said strips being supported in part by the tongues 18.

I use the terms longitudinal and lateral for the sake of convenience of description, and not to indicate that the longitudinal flanges are necessarily longer than the lateral flanges.

Having described my invention, I claim:

A box member composed of a blank having longitudinal creases near two opposite edges defining the bases of two longitudinal flanges and slots at the opposite ends of said creases defining the inner edges of reinforcing

tongues and the ends of two lateral flanges, the blank being also creased to define the bases of said lateral flanges, the said flanges being bent at right angles with the body portion to form a rectangular wall, said tongues being bent to overlap the end portions of the lateral flanges, and the longitudinal flanges and tongues being provided with reinforcing strips cemented to the inner sides of the said flanges and tongues and extending across the corners of said wall, each flange being widened, and centrally creased longitudinally to define the bases of flaps, which are of substantially the same width as the flanges and are bent inwardly to cover and conceal said tongues and reinforcing strips, and the inner sides of the flanges, the said flanges, strips, tongues, and flaps being cemented together and forming a laminated wall the corners of which are reinforced by both the said tongues and the said strips.

In testimony whereof I have affixed my signature, in presence of two witnesses.

ELLON S. HILL
